Primary Examiner — John Windmuller*Assistant Examiner* — John R Yeh(74) *Attorney, Agent, or Firm* — Lippincott IP LLC(57) **CLAIM**

The ornamental design for a cable tidy, as shown and described.

DESCRIPTION

FIG. 1 is a front, right-side perspective view of the cable tidy showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear, bottom, right-side perspective view thereof; and,

FIG. 9 is a front, bottom, left-side perspective view thereof. The broken lines in the figures represent features of the device which form no part of the claimed design.

1 Claim, 9 Drawing Sheets(56)
